F. H. Richards.

UNITED STATES PATENT OFFICE.

HENRY S. CHAPMAN, OF GLENRIDGE, NEW JERSEY.

PLAYING-BALL.

SPECIFICATION forming part of Letters Patent No. 711,474, dated October 21, 1902.

Application filed August 7, 1902. Serial No. 118,780. (No model.)

To all whom it may concern:

Be it known that I, HENRY S. CHAPMAN, a citizen of the United States, residing in Glenridge, in the county of Essex and State of New Jersey, have invented certain new and useful Improvements in Playing-Balls, of which the following is a specification.

This invention relates to golf-balls; and its object is to improve the construction thereof 10 to the end of rendering the ball more desirable in the game.

In the accompanying drawings, Figure 1 illustrates, partly in section, the preferred form of ball. Fig. 2 illustrates another form, 15 and Fig. 3 shows still another form.

For the filling of the ball I prefer to use a sphere 1, which may consist wholly or mainly of rubber. Upon this filling I prefer to apply a shell consisting of an inner layer or 20 sphere 2 of gutta-percha and an outer adherent or integral sphere or cover 3, consisting of gutta-percha compounded with a metallic substance, preferably oxid of zinc, said layers 2 and 3 being preferably put on under heat 25 and pressure and holding the rubber sphere 1 under high compression.

The cover 3, which may be very thin, is much lighter in color than ordinary gutta-percha, by reason of which the ball may be 30 easily found in the grass. The cover has preferably a light grayish tint. This compound of oxid of zinc and gutta-percha makes a shell or cover which is denser and less lively than plain gutta-percha and makes the ball 35 more desirable for "putting," while owing to its adherence or integrality it is not liable to become separated from the plain gutta-percha layer 2, and the duplex cover 2 3 is not liable to peen under the blows of the club, 40 and thereby become enlarged and separated from the rubber sphere 1. Other advantages will hereinafter appear.

In the form shown in Fig. 2 a layer A of the compound of gutta-percha and zinc is 45 placed between the inner rubber sphere 1 and the outer shell B, which may consist of plain gutta-percha. Owing to its extremely adhesive quality said layer A acts as a binder

between the outer shell B and the inner rubber sphere 1, said binder adhering on both 50 sides and firmly uniting the cover to the core, while owing to its relative inelasticity it prevents too high an activity of the ball under a light blow.

In Fig. 3 I show my improved compound in 55 the form of a thin shell 3^a upon a sphere C of either rubber or solid gutta-percha, where it has the advantage of furnishing an indestructible light-colored cover for the ball, while adhering firmly thereto and reducing 60 the resiliency thereof, as explained in connection with Fig. 1. If desired, the entire ball may be made of the compound of gutta-percha and oxid of zinc.

Variations may be resorted to within the 65 scope of my improvements.

Having described my invention, I claim—

1. A playing-ball comprising a sphere of elastic material, a sphere of gutta-percha thereon, and a cover compounded of gutta-percha and a metallic substance upon said 70 gutta-percha sphere.

2. A playing-ball comprising a sphere of elastic material, a sphere of gutta-percha thereon, and a cover compounded of gutta-percha and oxid of zinc upon said gutta-percha sphere. 75

3. A playing-ball comprising a sphere of elastic material, a sphere of gutta-percha thereon, and a cover compounded of gutta-percha and metal upon said gutta-percha sphere and integral therewith. 80

4. A playing-ball comprising a sphere of elastic material, a sphere of gutta-percha thereon, and a cover compounded of gutta-percha and oxid of zinc upon said gutta-percha sphere and integral therewith. 85

5. In a playing-ball, the combination of a sphere of rubber, a sphere of gutta-percha thereon and adhering thereto, and a sphere 90 of gutta-percha compounded with oxid of zinc; said gutta-percha sphere being integral.

HENRY S. CHAPMAN.
